DESIGN FOR A SPECTACLE CASE

Altina Barrett and Eric Barrett,
Hollywood 46, Calif.

Application February 24, 1945, Serial No. 118,126

Term of patent 7 years

(Cl. D57—1)

To all whom it may concern:

Be it known that we, Altina Barrett and Eric Barrett, citizens of the United States, residing at Beverly Hills, in the county of Los Angeles and State of California, have invented a new, original, and ornamental Design for a Spectacle Case, of which the following is a specification, reference being had to the accompanying drawing, forming part thereof.

In the drawing,

Fig. 1 is a front view of a spectacle case showing our new design;

Fig. 2 is a rear view of the same spectacle case; and

Fig. 3 is an elevational view of the open end of the spectacle case.

We claim:

The ornamental design for a spectacle case, substantially as shown.

ALTINA BARRETT.
ERIC BARRETT.
